UNITED STATES PATENT OFFICE.

FERDINAND E. CANDA, OF NEW YORK, N. Y.

CATTLE-CAR.

SPECIFICATION forming part of Letters Patent No. 450,504, dated April 14, 1891.

Application filed August 24, 1885. Serial No. 175,221. (No model.)

To all whom it may concern:

Be it known that I, FERDINAND E. CANDA, of the city, county, and State of New York, have invented a new and Improved Cattle-
5 Car, of which the following is a full, clear, and exact description.

My invention relates to the construction of that form of car used to transport cattle in one direction and freight in the other, the 10 object of the invention being to provide such cars with movable partitions or gates which, when not in use, may be moved to a position beneath the car-roof; and to this end the invention consists of a car divided into compartments by movable skeleton partitions 15 consisting of bars united by springs, said partitions being operated by endless chains that are secured to the lower bar, and of certain other constructions and combinations of parts, 20 as will be hereinafter described, and specifically pointed out in the claims.

Reference is to be had to the accompanying drawings, forming part of this specification, in which similar letters of reference indicate 25 corresponding parts in all the figures.

Figure 1 is a vertical cross-sectional view of a car constructed in accordance with the terms of my invention. Fig. 2 is a longitudinal vertical sectional view of the same. Fig. 30 3 is an enlarged sectional view of one of the chain-wheels. Fig. 4 is a detail view illustrating the construction of the crank-ratchet and pawl of the operating-shaft. Fig. 5 is a detail view of one of the flanged collars 35 through which the lifting-chains pass. Figs. 6 and 7 show modifications of details.

My improvements may be applied to the ordinary form of box or cattle-car such as partly shown in the drawings above referred 40 to, wherein A A represent the sills, B B the corner-posts, C C the intermediate posts, D D the plates, E E the earlings, and F the ridge-pole, of the car.

The sliding partitions shown at N are composed of a number of bars a a, united in a 45 peculiar and novel manner. There is no rigid connection between the bars a a, said bars being clamped to two or more springs c c by clips b b, depressions or recesses d d being 50 formed in the bars a a, in order that the springs c c may be clamped in beneath the

surface of the bars, the idea being to cause the springs to cant or tilt the bars within the grooves or runs in which the partition is mounted, thus creating a certain amount of 55 friction between the bars of the partition and the cleats forming the runs or ways, which will be sufficient to prevent the partition from sliding down with a rush when being lowered from the upper grooves to its normal position across the car. In fact the friction is 60 sufficient to hold the partition in any position to which it may be moved.

The grooves or runs e, h, and i, in which the partitions N are operated, are formed by 65 strips or cleats, as f f', secured to the posts C C, strips g g, secured to the upper side wall k, and plates D D and segments H H, secured to the posts and side walls, as best shown in Fig. 2.

It will be noticed that the side walls n n' of the segments H H are not concentric; in fact, that the radius of the upper wall n is less than that of the lower wall n', thereby making the ways or runs h h wider at the 75 middle of the segments than at the ends. It will also be noticed that when the gate or partition N is placed in position the springs c c are on the side toward the centers of the segments H H, the partition being so placed 80 in order that when it is raised the springs will tilt the bars, so that they will not bind within the curved ways h h, and it is to further assist the motion of the bars through said curved ways that the segments H H are 85 constructed with non-concentric walls n n'.

The endless chains o o, by which the partitions N are operated, are held by sheaves p p and chain-wheels s s, said chain-wheels being fast to a shaft S, which passes through 90 and rides in bearings formed in the sills A A. The openings in the floor through which the chains o o pass are protected by flanged collars c', which project upward an inch or so above the floor, and thus prevent any of the 95 bedding or excrement from falling upon and fouling the chain-wheels. These wheels s s are formed with grooved peripheries, in which the chains o o rest, the bearing-surface of the wheels consisting of alternate depressions t t' and lugs t t, said lugs being arranged to enter every other link of the chains, thus ren- 100

dering the movement of the chains positive. The action of the chains *o o* being positive, the attendant can readily separate the cattle into different stalls by simply lowering the 5 partitions and forcing the animals to move to one side or the other.

Each end of the shaft *S* is formed to fit the socket of a crank-handle *L*, and one or both ends of the shaft *S* or are provided with a 10 ratchet-wheel *w*, arranged to engage with a pawl *w'*. The pawl and ratchet need, however, only be used in the event of the breaking of a gate-spring, as when the parts are in working order the action of the springs will 15 hold the gate or partition in place; but when a spring is damaged or broken the partition is raised into the grooves *i i* and the pawl *w'* set to hold the parts in place, thus transforming two single stalls into one double one 20 and in no way disabling the car.

The inner arm *q'* of the blocks *q*, in which the sheaves *p p* are mounted, is extended downward and longitudinally slotted at *q'*, and through this slot there is passed a bolt 25 that is rigidly fixed in the block *p'*, which is secured to the post *C*, the block *q* being held against the block *p'* by a nut *p*², this construction being adopted in order that the sheaves *p p* may be adjusted to take up slack 30 in the chains *o o*.

Instead of the construction just described for adjusting the sheaves *p p*, I sometimes prefer to use such a device as is illustrated in Figs. 6 and 7, wherein the block *q* is shown 35 as being made integral with a slotted plate *g'*, that is provided with a feather *g*², which rides in a groove formed in the post *C*, the plate being clamped to place by two tap-screws *v' v'*.

40 The chains *o o* are secured to the lower part, and preferably to the lower bar of the movable partition *N*, and by this novel connection I am able to completely control the movement of the partition irrespective of the 45 position in which it may be placed.

In order that the springs *c c* may be relieved of any compressive strain in supporting the weight of the partition *N*, I provide the top bar with pins *v'*, arranged to rest on 50 stops *v*, secured to the cleats *f*, when the partition is lowered to the position shown in the drawings, the position of the pins *v'* and stops *v* being such that when the partition is lowered to its normal position just above the 55 floor, as shown, the stops or pins will come in contact and support the gate, and it consequently follows that the strain on the springs

will be a tensile rather than a compressive strain, and it will be understood that should an animal rise and throw its weight upon the 60 gate the strain on the springs would still be a tensile strain, as the gate is entirely supported from above, that is from its top rail.

Such partitions as I have described may be operated from either side of the car by an attendant standing on the ground, who simply applies the crank-handle and rotates the shaft *S* to move the partitions to the required position, and after the cattle have been discharged the partitions may be raised within 70 the grooves *i i*, where they do not take up useful space.

Having thus described my invention, I claim as new and desire to secure by Letters Patent—

75 1. The partition or gate *N*, consisting of a series of bars united by springs, substantially as described.

2. The gate or partition *N*, consisting of a series of bars constructed with recesses and 80 united by springs which rest and are secured within said recesses, substantially as described.

3. The combination, with a gate or partition consisting of a series of bars united by 85 springs, of cleats *f f'* and *g g* and segments *H H*, formed with non-concentric walls *n n'*, thereby forming ways *e h*, and *i*, and a lifting or operating mechanism consisting of chains *o o*, secured to the bottom bar of the 90 partition and passing over sheaves *p p* and chain-wheels *s s*, carried by a shaft *S*, mounted in the sills *A A*, substantially as described.

4. In a stock-car, partitions consisting of slats or bars connected by flexible strips of 95 sufficient stiffness to maintain the slats in position, said partitions being fitted to guides and connected at one end only to the propelling mechanism, but adapted to be moved thereby in both directions in combination 100 with said propelling mechanism, substantially as described.

5. In a stock-car, partitions consisting of bars or slats connected by flexible strips of 105 sufficient stiffness to maintain the slats in position, said partitions being fitted to guides and connected at one end only to endless chains adapted to move the partitions in both directions, all in combination, substantially as described.

FERDINAND E. CANDA.
